BOLSTER CONSTRUCTION FOR RAIL CAR
UNDERFRAMES

Albert G. Dean, Narberth, Pa., assignor to Edward G. Budd Manufacturing Company, Philadelphia, Pa., a corporation of Pennsylvania

Original application November 21, 1941, Serial No. 419,816, now Patent No. 2,331,891, dated October 19, 1943. Divided and this application October 15, 1943, Serial No. 506,332

13 Claims. (Cl. 105—226)

1

The invention relates to a rail car underframe and particularly to the bolster construction and associated parts of such an underframe.

The present application is a division of applicant's co-pending application Serial No. 419,816 filed November 21, 1941, now Patent No. 2,331,891, issued October 19, 1943, entitled End underframe construction for rail cars, which, in turn, is a continuation-in-part of applicant's formerly co-pending but now abandoned application Serial No. 296,026, filed September 22, 1939, entitled Rail car underframe.

As in the parent applications, one of the main objects of the invention is to provide an underframe of the class which, for standard size railway cars, is of light weight as compared with known such underframes and yet one which acts to absorb the heavy draft and buffing loads as well as to take the extremely heavy collision shocks incident to railway car operation and which meets with A. A. R. requirements to substantially the same or even greater degree as previous heavy type underframes.

It is a further object of the invention to provide an underframe structure which can be readily assembled in subassemblies by spot welding, and which subassemblies are as readily joined together in final assembly and to adjoining side and end wall structures of the body, the latter also being preferably of light weight construction.

To the end of achieving these objects, substantially the entire underframe, including the bolsters, transverse floor beams, longitudinal stringers, center and side sills and flooring, as well as the end sills, and the buff and draft gear housing center sill extensions connecting the end sills to the bolsters and center sill proper are constructed, in the main of light-gauge members which may be rolled or drawn sections of strip stock and which are so formed in their margins as to facilitate joinder to each other and into the body structure as a whole, as by spot welding.

To this end also, the center sill end extensions of the underframe connecting the end sill to the bolster and center sill proper, the bolster and the center sill proper may all be assembled as separate subassemblies, the parts of which are so formed as to be readily so subassembled and joined together in final assembly.

The bolster, in particular, is a separate subassembly, preferably of box section form in cross section, and so designed as to facilitate its attachment in final assembly to the adjacent parts

2

of the underframe and body side walls in final assembly. It is reinforced in regions of maximum stress, as in the region of the center sill and in the side bearing regions.

Other and further objects and advantages and the manner in which they are attained will become apparent from the following detailed description when read in connection with the accompanying drawings forming a part hereof.

10 In the drawings:

Fig. 1 is a partial transverse sectional view through the underframe, the section being taken substantially along the line 1—1 of Fig. 2, looking in the direction of the arrows.

15 Fig. 2 is a fragmentary longitudinal sectional view, the section being taken substantially along the line 2—2 of Fig. 1, but the center sill proper being shown in elevation.

Fig. 3 is a fragmentary plan view of the bolster and associated parts, the side wall post connected to the bolster being shown in horizontal section.

20 Fig. 4 is a fragmentary horizontal sectional view through the bolster and associated parts, the section being taken substantially on the line 4—4 of Fig. 1.

25 Figs. 5, 6 and 7 are fragmentary detail sectional views taken substantially along the lines 5—5, 6—6 and 7—7, respectively, of Fig. 1.

30 The underframe according to the invention comprises the center sill proper 10 extending through the bolster 11 and having the end extensions 12 forming draft gear and buffer pockets between them and overlapping the end of the center sill proper and rigidly secured thereto and to the bolster. The underframe parts immediately associated with the bolster further comprise, the longitudinal floor stringers 13, the transversely corrugated flooring 14, the side sills, 35 15, and the side wall posts 16.

35 The center sill proper 10 may comprise, as appears in Figs. 1, 2, 3, 4 and 5, a compact columnar structure, built up of a plurality of sheet metal sections secured together as by spot welding. It 40 is of generally rectangular form and the corners of the rectangle are formed by angular formations 17 which provide accessibility for ready attachment of associated parts thereto. This form of sill is fully described and claimed in the patent above referred to and further description thereof except as it enters into the bolster construction of the invention, is believed unnecessary.

45 The bolster, as 11, is assembled as a separate subassembly unit and is built up in the main of

sheet metal parts. It comprises a box section structure whose top face is flat and whose bottom face, for some distance inwardly from its ends, is extended parallel to the top face and then inclined downwardly toward the center and provided with a flat portion at the center of somewhat greater width than the width of the center sill, Fig. 1. In the lower portion of this central deepened portion, the bolster is provided with a rectangular opening 18 to receive the center sill.

The box-section of the bolster is comprised, in the main, of a flat top plate 19, a flat bottom plate 20 and lateral channel section plates 21, these latter being of laterally facing channel cross section with their side walls overlapping the top and bottom plates and secured thereto by spot welding.

There are four such channel section plates 21, and in their central portion they terminate in their lower portions at the sides of the center sill receiving opening 18, but at their upper portions, they are extended inwardly over the center sill opening to have the upper portions of the two plates on each side of the bolster terminate in close proximity adjacent its center, see Fig. 1. These extended upper portions of the side plates 21 are strongly joined together in each case by a substantially J-section member 22 overlapping their inside faces by a wide overlap and secured thereto by numerous spot welds. As shown in Figs. 1 and 2, the bottoms of these J-section members terminate at the top of the opening 18 which receives the center sill, overlap the top flanges 17 of the sill and are secured thereto in the overlap.

The outer ends of the side plates 21 are extended at their ends beyond the top and bottom plates to overlap the side walls of channel section posts, as 16, of the side walls, to which they are secured in final assembly as by spot welding.

Additional reinforcement and provision for securing to the side wall posts is provided by a channel member 24 telescoped between the side plates 21 and having its bottom wall in position to overlap the bottom wall of the post, this channel being, in final assembly, spot welded to the bottom wall of the adjacent post 16 and to the side plates 21 in the subassembly of the bolster.

It is desirable to strongly reinforce the bolster against buckling in the region where the horizontal side portion of its bottom wall merges with the downwardly inclined bottom of the central portion, adjacent the region where the usual side bearing as 25 is provided. To this end, there is provided at this point a strong inner reinforcement which may consist of two channels 26 and 27 welded to an intermediate flat strip 28, which directly abuts the bottom wall of the bolster at this point. The side walls of the channels 26 and 27 telescope between the side plates 21 of the bolster and are strongly secured thereto by numerous spot welds.

Since the side bearing, as 25, is secured adjacent this region by bolting it to the laterally extending flanges formed by the side plates 21 and bottom plate 19, these flanges are further reinforced in this region by angle members 29 spot welded through one of their arms to the adjacent side plate 21 and through the other of their arms through the adjacent laterally extending flange through which the securing bolts extend, see Fig. 1.

At each side of the opening 18 receiving the center sill the bolster is further reinforced by tri-

angular spaced gussets 30 of substantially the height of the central portion of the bolster. These gussets have vertical flanges 31 paralleling the opening 18 and bottom flanges 32 overlapping the lower lateral flanges of the side plates 21 and are strongly secured to the side plates 21 in their overlapping body portions by numerous spot welds, see Fig. 1.

In the angle of their lower margins, the side plates 21 are further reinforced by an angle 33 nesting with the angle formed by the body of each gusset 30 and its bottom flange 32. In these regions of quadruple thickness sheet metal is secured the center plate casting 34 of the bolster, as by riveting, as shown at 35, through the four thickness of metal and an overlapping portion of the casting. Since the center plate casting spans the opening 18 in the bolster, and is strongly secured to the reinforced structure just described at the opposite sides of the opening, the entire bolster structure is strongly tied into the center plate. The casting 34 has spaced lateral extensions, as 36, overlapping the bottom flanged portions of the respective center sill end extensions 12 and securely riveted thereto to provide a strong connection of the bolster with the bottom portions of said extensions, see Fig. 4.

At the sides, the opening 18 of the bolster is further reinforced by vertical plates 37 overlapping the vertical flanges 31 of the gussets 30 and secured thereto. To these plates 37 are further secured at the four corners of the opening the angles 38 spot welded thereto through their vertical arms. These angles preferably extend some distance beyond the opposite sides of the bolster and form final assembly joints for securing the center sill proper 10 to the bolster. When the bolster is telescoped over the center sill in the final assembly, the angular corner portions 17 of the sill 10 overlap or nest with the angles 38 and are secured thereto in the overlaps by spot welding, see Figs. 1 and 5.

The top of the bolster 11 is arranged substantially in the plane of the flooring and at the top, the bolster may have its side plates formed with cut out openings, as 39, at spaced locations, see Fig. 1, and reinforced below said openings by angles, as 40, extending substantially the length of the bolster.

These cut out openings receive, in the subassembly of the bolster, short channels 41 extending beyond the inner and outer faces of the bolster and secured to the angles 40, and the top flanges of the side plates 21, through their side walls, the extended portions serving as final assembly joint parts to connect the floor stringers, as 13, see Figs. 2, 3 and 7. At the center, see Figs. 2 and 5, the two central members 41 overlap in final assembly the respective center sill end extensions 12 and are strongly spot welded thereto, to tie the bolster to the center sill end extensions adjacent the floor level. These end extensions may additionally be tied to the bolster by gussets as 42, see Fig. 2, overlapping the vertical flanges 31 of the gussets 30 and the adjacent center sill end extensions 12 and strongly spot welded to each.

For the last stringer 13 at the side, the cut out opening is not provided to avoid weakening of the bolster in this region of connection to the side wall of the body. At this location the construction is that shown in Figs. 1 and 6. An outwardly facing channel 43 is secured to the angle 40 and the adjacent top flange of the adjacent side plate of the bolster and a short channel, as

44, is telescoped into this channel and secured to its side walls, this channel projecting, like the channels 41, to serve as final assembly joint parts on the bolster to secure the adjacent ends of a floor stringer 13.

After the bolster subassembly has been assembled with the center sill proper and its end extensions as already described, the side wall subassembly, with its posts 16 and side sills 15 may be brought into place and secured thereto, by having the side sill overlap the top of the bolster and the posts secured between the side walls of the bolster as already described. The transversely corrugated flooring 14 may then be laid over and secured to the stringers 13 and side sills 15.

From the foregoing description, it can be seen that the bolster can be readily assembled as a subassembly unit, adapted to be readily joined in final assembly to the center sill and center sill end extensions by strongly reinforced joint structures and also to the longitudinal flooring stringers and side wall subassemblies. It is also seen that the bolster, except, for the center plate and side bearing castings is fabricated entirely of sheet metal members of relatively light gauge material so that an exceedingly light but strong bolster structure results.

What is claimed is:

1. In a rail car underframe, a bolster having a vertically deepened central portion, said bolster being a box cross-section fabricated of sheet metal, the side walls being outwardly facing channels and the top and bottom walls being continuous flat strips overlapping the side walls of the channels and secured thereto, the side walls being continuous in the upper portion but discontinuous in the lower portion of the bolster to provide an opening for the extension of a center sill through the bolster, and reinforcing members for said side walls extending around the sides and top of said opening and including means for attachment to the center sill.

2. In a rail car underframe, a bolster of box cross-section fabricated of flat top and bottom plates and outwardly facing channel side plates secured through their flanges to the top and bottom plates, the bolster side walls being cut away in their lower central portion to provide an opening to permit the passage through the bolster of a center sill, and reinforcing members flanking said opening including means for attachment to the center sill in final assembly.

3. In a rail car underframe, a bolster having its top arranged substantially in the plane of the floor and having transversely spaced, longitudinally extending openings therethrough adjacent its top, spaced angular strips extending through the openings in the bolster below its top, secured thereto and projecting from its opposite faces to provide means for attaching longitudinally extending stringers of the underframe to the bolster.

4. In a rail car underframe, a box cross-section bolster fabricated in the main of sheet metal members, comprising top and bottom through running members and side members of varying vertical depth interconnecting said top and bottom members, the central portions of said side members being deepest and provided with an opening in their lower portion for the passage of a center sill therethrough, reinforcing members for said side members, flanking the top and sides of said opening and providing final assembly joint parts for attaching the bolster to the center sill.

5. In a rail car underframe, a box cross-section bolster fabricated of sheet metal members, including top and bottom through running members and side members of varying vertical depth interconnecting said top and bottom members, the central portions of said side members being deepest and provided with an opening in their lower portions for the passage of a center sill therethrough, reinforcing elements for said side members extending respectively, across the top and sides of said opening and some distance therewith at top and sides to provide wide overlaps between said elements and the side members and, at the top, between said top and side reinforcing elements, and a center plate bridging said opening and secured to the reinforced side members on opposite sides thereof.

6. A bolster subassembly for rail car underframes having its top arranged substantially in the plane of the floor and laterally flanged, the bolster being cut out at spaced locations below said flange and reinforced by an angular member secured below said cut out portion and paralleling said lateral flange, and angular strips passing through said cut out portions and projecting at the opposite sides of the bolster, said strips being secured both to the lateral flange and said angular reinforcing member paralleling the flange.

7. A bolster subassembly for rail car underframes, comprising a box cross-section beam, deeper at the center than at its ends and fabricated of through running top and bottom members interconnected by laterally facing channel side members, the side members being formed with an opening in the lower central portions thereof for the passage of a center sill, reinforcements for said side members flanking the sides and top of said opening, and a center plate bridging the opening and secured at opposite sides of said opening to said reinforced portions flanking the sides of the opening.

8. A bolster for rail car underframes, comprising a box section beam of greater depth centrally than at its sides and including flat top and bottom members interconnected by channel section side members, the side members being formed with an opening in their lower portions for receiving a center sill therethrough, reinforcing members connected to said side members above said opening and extending a substantial distance on each side thereof, and further reinforcing members flanking the sides of said openings and extending into overlapping relation with the reinforcing members extending above said opening.

9. In a rail car underframe, a bolster of hollow cross-section fabricated of top and bottom plates and outwardly facing channel side plates secured through their flanges to the top and bottom plates, the bolster side walls forming an opening in the lower central portion of the bolster to permit the passage through the bolster of a center sill, and reinforcing members flanking said opening including means for attachment to the center sill in final assembly.

10. In a rail car underframe, a hollow cross-section transverse bolster beam, deeper at the center than at its ends and fabricated of through running top and bottom members interconnected by laterally facing channel side members, the side members providing an opening in the lower central portions of the beam for the passage of a center sill, reinforcements for said side members flanking the sides of said opening, and a center plate bridging the opening and secured at oppo-

site sides of said opening to said reinforced portions flanking the sides of the opening.

11. In a rail car underframe, a bolster having a vertically deepened central portion, said bolster being a hollow section fabricated of sheet metal and having side walls in the form of outwardly facing channels and a bottom wall in the form of a continuous flat strip overlapping the side walls of the channels and secured thereto, the side walls being continuous in the upper portion but discontinuous in the lower portion of the bolster to provide an opening for the extension of the center sill through the bolster, and reinforcing members for said side walls extending around the sides and top of said opening and including means for attachment to the center sill.

12. In a rail car underframe, a hollow cross-section bolster fabricated of sheet metal members, including a bottom through-running member and side members of varying vertical depth interconnected by said bottom member, the central portions of said side members being deepest and interrupted at least in their lower portions to provide an opening for the passage of a center

5
10
15
20

sill therethrough, reinforcing elements for said side members extending, respectively, across the top and sides of said opening and some distance therebeyond at top and sides to provide wide overlaps between said elements and the side members and, at the top, between said top and side reinforcing elements, and a center plate bridging said opening and secured to the reinforced side members on opposite sides thereof.

13. A bolster for rail car underframes, comprising a hollow-section beam of greater depth centrally than at its sides and including a bottom member interconnecting channel-section side members, the side members forming an opening in the lower portion of the beam for receiving a center sill therethrough, reinforcing members connected to said side members above said opening and extending a substantial distance on each side thereof, and further reinforcing members flanking the sides of said openings and extending into overlapping relation with the reinforcing members extending above said opening.

ALBERT G. DEAN.
